UNITED STATES PATENT OFFICE.

JULES H. VENON, OF NEW YORK, N. Y.

DESIGN FOR A GOBLET OR SIMILAR ARTICLE.

Application filed February 16, 1928. Serial No. 25,460. Term of patent 14 years.

To all whom it may concern:

Be it known that I, JULES H. VENON, a citizen of the United States, and resident of the city, county, and State of New York, have invented a new, original, and ornamental Design for a Goblet or Similar Article, of which the following is a specification, reference being had to the accompanying drawing, forming part thereof.

In Fig. 1 of the drawing is shown, in elevation, a goblet embodying my new design. Fig. 2 is a plan view, in section, on the line 2—2 of Fig. 1.

I claim:

The ornamental design for a goblet or similar article, as shown.

JULES H. VENON.
